To all whom it may concern:

Be it known that I, John S. Davy, of Troy, in the County of Rensselaer, and State of New York, have invented or produced a new and useful design of a jamb or side plate for a cook stove, which I call the "Troy Sun" and I do hereby declare that the following is a full clear and exact description of the same, reference being had to the annexed drawings making a part of this specification in which fig. 1. is a direct view of the jamb-plate, and figures 2, and 3, are sectional views, showing the curves of the plate and mouldings.

The ornamental design of my stove jamb or side plate consists of the ornaments A, and B, arranged on the panels of the oven doors C, and D, and the ornament E, arranged on the raised panel F, also in the sunk panel G, and ornamental borderings (aa, bb, cc,) disposed on the oven doors, raised panel, and mouldings.

Having thus described my new design of jamb plate for cook stove-

What I Claim as new and desire to secure by Letters Patent is, the ornamental design and configuration of jamb plate for a cook stove, such as herein described and represented in the annexed drawing.
